UNITED STATES PATENT OFFICE

163,500

COMBINED SUNDIAL AND PAPERWEIGHT

Ruth Watts, Bellaire, Tex.

Application June 20, 1949, Serial No. 3,418

Term of patent 3½ years

(Cl. D42—7)

To all whom it may concern:

Be it known that I, Ruth Watts, a citizen of the United States of America, residing at Bellaire in Harris County, Texas, have invented a new, original, and ornamental Design for a Combined Sundial and Paper Weight, of which the following is a specification, reference being had to the accompanying drawing, forming a part hereof, wherein:

Figure 1 is a plan view of the combined sundial and paper weight, showing my new design;

Figure 2 is a front elevational view thereof; and

Figure 3 is a side view thereof.

What I claim is:

The ornamental design for a combined sundial and paper weight, as shown.

RUTH WATTS.
